Des. 194,400
Patented Jan. 15, 1963

194,400

GAME BOARD

Richard J. Puglisi, 352 Conklin Ave.; Robert Spiegel, 198
Conklin Ave.; and Edward G. Pucek, 7 Mill St., all of Binghamton, N.Y.

Filed Oct. 16, 1961, Ser. No. 67,076

Term of patent 14 years

(Cl. D34—5)

The FIGURE is a plan view of a game board of conventional thickness showing our new design.

The dominant features of our design reside in the portions shown in full lines.

We claim:

The ornamental design for a game board, as shown and described.
